PORTABLE FOLDING TOILET SEAT

Manford E. Dahle, Franklin, Va.

Application November 10, 1944, Serial No. 562,764

4 Claims. (Cl. 4—239).

1

The invention relates to portable toilet seats. One object of the invention is to provide a portable or child's toilet seat which is adapted to be used on a permanently-installed toilet and is conveniently foldable for carrying purposes or storage.

Another object of the invention is to provide an improved portable or child's toilet seat which is simple in construction and composed of sections which can be folded together in lapped and substantially parallel relation and into a small and compact unit.

Other objects will appear from the detailed description.

The invention consists in the several novel features hereinafter set forth and more particularly defined by claims at the conclusion hereof.

In the drawings:

Fig. 1 is a perspective of a portable and foldable toilet seat embodying the invention in position for use on a permanently installed toilet.

Fig. 2 is a perspective of the portable toilet seat viewed from its lowered side.

Fig. 3 is a perspective of the portable toilet seat partially folded.

Fig. 4 is a perspective of the portable seat in fully folded position.

Fig. 5 is a side elevation of the portable seat unfolded for use.

The invention is exemplified in a portable toilet seat which is adapted to be directly placed in usable position on the toilet seat A of permanently installed toilet B which may be of usual construction.

The portable toilet seat of the invention comprises four corner sections which are pivotally connected so they can be folded together on the longitudinal and transverse centers of the seat. Each of these sections may be formed of suitable flat stock, such as plywood, plastic or other lightweight material. For lightness in weight, stock approximately $\frac{1}{4}$ " in thickness may be used.

The foldable toilet seat comprises a pair of rear corner sections 10 and 11 which have longitudinally extending contiguous or meeting edges 12 at the longitudinal center of the seat, and are of like contour so that they can be folded together transversely into lapped position. The rear sections 10 and 11 are pivotally connected together along their contiguous edges 12 by a hinge 13 which is secured on the underside of the sections and on blocks or members 14 which space the hinge 13 from the plane of the underside of said sections.

2

The front corner sections 15 and 16 are of like contour and have rear edges which are contiguous with the front edges of sections 10 and 11 along the transverse center of the seat. A hinge 17 is secured to the underside of front section 15 and rear section 10, and a similar hinge 18 is secured to the underside of front section 16 and rear section 11. Hinges 17 and 18 pivotally connect the front sections to the rear sections along their contiguous edges, so the front and rear sections at each side can be folded into lapped or substantially parallel relation. The contiguous edges of the front and rear sections are formed on an angle of about 45° to avoid pinching of any part of a child.

An opening 20 of suitable contour in the portable seat is symmetrically formed in the front and rear sections. The inner edges 21 of the front sections are spaced apart to provide a slot 20 communicating with the usual opening in the divided seat A.

A downward-facing, resilient suction cup 23 is suitably secured to the underside of each of the front sections 15 and 16. These cups are adapted, when pressed against the permanently installed seat, to retain the folding seat against lateral slippage.

When the unfolded portable seat is laid on the permanently installed seat A, as illustrated in Fig. 1, the top face of the folding seat will be flat and smooth, the front sections of the portable seat will be supported in vertical spaced relation from the top of seat A by the suction cups 23 and the hinge 13 will rest on the seat A so that the portable seat will be horizontally positioned and will be held against lateral slippage by cups 23.

When it is desired to fold the portable seat for convenient carrying or for storage, the front corner sections 15 and 16 are first folded to lap the rear sections 10 and 11, respectively, as illustrated in Fig. 3; then, the front and rear sections at one side and the front and rear sections at the other side are folded together as illustrated in Fig. 4. When thus folded, the portable seat will form a small compact unit which can be easily packed and carried in readiness for occasional use.

The invention exemplifies a portable or child's toilet seat which comprises four corner sections which may be formed of flat, lightweight stock and can be folded together into a compact unit. The rear sections are pivotally connected at the longitudinal center of the seat, so that the edges will be conterminous when folded to-

gether and the front sections are pivotally connected to the rear sections at the longitudinal center of the seat, so that the edges of the front and rear sections will be substantially conterminous and all of the sections will snugly fold together. The hinges between the sections are disposed on the underside of the seat, so that the top face of the seat, when unfolded, will be smooth with flush edges between the sections. The front sections are foldable together between the rear sections, when the portable seat is fully folded, as illustrated in Fig. 4.

Having thus described the invention, what I claim as new and desire to secure by Letters Patent is:

1. A portable toilet seat comprising, a pair of rear sections of substantially thin light-weight material, having contiguous edges substantially at the longitudinal center of the seat, a pair of front sections of like material, having rear edges contiguous to the front edges of the rear sections substantially at the transverse center of the seat and having confronting inner edges spaced apart to form a gap therebetween, spacer blocks on the underside of and at the contiguous edges of the rear sections and foldable into the gap between the front sections, a hinge secured to the spacer blocks having its hinge-axis below the underside of the rear sections, and hinges between and secured on the underside of the front and rear sections, the front sections being foldable with their underfaces in confronting relation with the underfaces of the rear sections, the hinge between the rear sections being adapted for folding the front sections between the rear sections and into substantially parallel relation therewith.

2. A portable toilet seat comprising, a pair of rear sections of substantially thin light-weight material, having contiguous edges substantially at the longitudinal center of the seat, a pair of front sections of like material, having rear edges contiguous to the front edges of the rear sections substantially at the transverse center of the seat, and confronting inner edges spaced apart to form a gap between them, a hinge for said contiguous edges of the rear sections, means for securing said hinge to and spacing its hinge-axis below the underside of the rear sections, and hinges between and secured on the underside of the front and rear sections, the front sections being foldable with their underfaces in confronting relation with the underfaces of the rear sections, with the spacing means in the gap between their inner confronting ends, the hinge between the rear sections being adapted for folding the front sections between the rear sections and into substantially parallel relation therewith.

3. A portable toilet seat comprising, a pair of rear sections of substantially thin light-weight material, having contiguous edges substantially

at the longitudinal center of the seat, a pair of front sections of like material having rear edges contiguous to the front edges of the rear sections substantially at the transverse center of the seat, and confronting inner edges spaced apart to form a gap between, a hinge between said contiguous edges of the rear sections, blocks for said hinge on and for spacing its hinge-axis below the plane of the underside of the rear sections and foldable into said gap, and hinges between and secured on the underside of the front and rear sections, the front sections being foldable with their underfaces in confronting relation with the underfaces of the rear sections, with the blocks extending into said gap, the hinge between the rear sections being adapted for folding the front sections between the rear sections and into substantially parallel relation therewith.

4. A portable toilet seat comprising, a pair of rear sections of substantially thin light-weight material, having contiguous edges substantially at the longitudinal center of the seat, a pair of front sections of like material having rear edges contiguous to the front edges of the rear sections substantially of the transverse center of the seat and having confronting inner edges spaced apart to form a gap between them, a hinge for said contiguous edges of the rear sections, means for securing said hinge to and spacing its hinge-axis below the underside of the rear sections, and hinges between and secured on the underside of the front and rear sections, said means and hinges being adapted to support the rear section on a permanent seat, and abutments secured on the underside of the front sections adapted to support the front sections on a permanent seat, said means and hinge and said abutments being of substantially the same height, the front sections being foldable with their underfaces in confronting relation with the underfaces of the rear sections, the hinge between the rear sections being adapted for folding the front sections between the rear sections and into substantially parallel relation therewith, said means and hinge and abutments being adapted to space the rear sections apart and in substantially parallel relation when they are folded with the front sections between them.
